DISPLAY RACK

Herbert W. Tinker, Milwaukee, Wis., assignor to
 Lyen Cover Company, Detroit, Mich., a corpora-
 tion of Michigan

Application May 26, 1933, Serial No. 672,994

5 Claims. (Cl. 211—133)

This invention has to do with display racks and is concerned more particularly with a display rack which is made of sheet material such as metal.

5 It is an object of the present invention to utilize what would otherwise be scrap material in the production of sheet metallic articles such as display racks.

It is another object of the invention to employ the by-products remaining after the manufacture of tire covers, for the manufacture of metallic articles such as display racks.

10 It is a further object of the invention to employ a novel method of manufacture of a sheet metal article, substantially all of whose parts are stamped from the material remaining after removal of material to be employed as a tire cover.

15 It is another object of the invention to employ an entire circular blank of sheet metal by cutting the same into a plurality of parts all of which constitute salient parts of a display rack or stand.

20 Another object of the invention resides in the arrangement and shape of material parts of a display stand so that the same, before being formed, together constitute a complete circle and, after being formed, constitute the framework of a display stand.

25 Other objects of the invention are to provide: a display stand affording means whereby the same may be supported by legs or, selectively, suspended; a device of this character which is extremely attractive, and affords means for supporting a mirror and for supporting articles in front of the mirror; a display stand which is compact, may be manufactured at a lower cost than would be the case if the principles of the present invention were not followed; a display 30 rack which is dependable in use and is durable, and may be finished in any desired color or design of enamel or may be chrome plated or otherwise finished to provide the desired esthetic effect.

35 In accordance with the general features of the invention, a generally square blank which is employed in the manufacture of tire cover annular side plates, has an annular portion thereof removed for that purpose. The central blank and 40 the irregular annular piece remaining have heretofore been sold as scrap at a price very substantially below the price at which the material is originally purchased. The present invention contemplates the retention of the circular blank in its entirety and selected portions

45 of the irregular annular piece. To this end, the circular piece in accordance with the present invention is cut through along an arc parallel to its periphery and preferably in excess of 180° and along the chord connecting the ends of said arc. The part-circular piece thus defined is itself sheared along a chord which may be substantially parallel to and of substantially the same length as the first chord. The segment thus remaining is divided by a radial cut preferably bisecting the second chord. Thus from the original circular blank, we have a pair of complementary brace or bracket parts together constituting a segment of the circle along which the original cut was made, a platform or shelf member having arcuate ends and longitudinal edges between the ends, and a generally annular frame piece remaining, said piece being substantially circular throughout more than 180° and substantially segmental throughout the remaining portion thereof.

50 Of course the angle through which the original arcuate cut is made may be varied, and the shapes of the parts severed from the original circular blank may also be varied, to effect different sizes of parts of the stand.

55 The platform member is provided with an angular lip at one margin for engaging an abutment portion at the chord of the frame and extends rearwardly therefrom. The bracket parts are positioned between an abutment on the lower part of the frame and the platform to support the latter at the desired angle for displaying the desired articles. The irregular annular piece remaining after the tire cover side plate is blanked out of the original substantially square blank affords sufficient material from which details such as retaining elements and legs may be stamped out. The legs and other details are suitably secured as by spot welding, rivets or the like to afford a support for the stand. A strip which may be severed from the shelf member or from other stock may be secured to the member to form a mirror receiving panel or groove, and a hanger which may be formed from other stock may be suitably secured preferably to the upper part of the stand to afford a means for supporting the stand by suspension instead of upon legs.

60 Other and further important objects of this invention will be apparent from the disclosures in the specification and the accompanying drawings.

65 This invention (in a preferred form) is illus-

55

trated in the drawings and hereinafter more fully described.

On the drawings:

Figure 1 is a view showing a tire cover side plate blank from which the annular piece forming the tire cover side plate has been removed, and also showing how the remaining material is stamped out to afford substantially all of the parts necessary to the construction of the display stand.

Figure 2 is a front elevation of a display stand or rack constructed in accordance with the principles of the present invention.

Figure 3 is a vertical sectional view taken substantially in the plane designated by the line III—III in Figure 2.

Figure 4 is a plan view of Figure 2.

Figure 5 is a fragmentary rear view of Figure 2, somewhat enlarged.

Figure 6 is a fragmentary sectional view taken substantially in a plane designated by the line VI—VI in Figure 3.

Figure 7 is an enlarged sectional view of the shelf portion of the display rack.

Figure 8 is an elevational view of an auxiliary supporting member or hanger for use when the rack is to be suspended instead of supported on legs.

Referring now more particularly to the drawings, the reference character 1 designates generally a substantially square blank of sheet metal which, prior to any operation thereupon, is imperforate. Blanks of this shape and appropriate size are employed in the manufacture of side plates for tire covers. These side plates, when stamped out, are flat and circular as indicated by the space 2, and each is ultimately formed to cover a side wall of a tire and to be held thereon as by a resilient split ring which embraces and covers the tire tread.

In the past, the material remaining after the cutting of the circular part indicated by the reference character 2 has been nothing more than scrap, resold at a small fraction of the pro rata cost of the same in the blank 1. The amount of material thus constituting the scrap is obviously very considerable and the financial loss involved has accordingly been very substantial. In accordance with the present invention, a major portion of the material which heretofore has constituted scrap is employed in the construction of a novel display stand or rack. To this end, the center disc 3 is trimmed of a narrow annulus 4, leaving a disc 5a which is to constitute the major part of the stand.

The disc 5a is formed with a preferably concentric arcuate cut 6 of an extent preferably more than 180°, leaving free an area correspondingly less than a circle as shown at 7. At the ends 8 of the arcuate cut 6, the material is further cut or stamped to form notches 9, and the material of the disc 5a is also severed along the chord 10 extending between the ends 8 of the arc 6. Thus, of the inner disc which would have been formed by making the arcuate cut 6 endless, the segment formed by the chord 10 and a continuation of the cut 6 remains integral with the remaining arcuate strip constituting the frame 5.

At the time the cuts at 6, 9, and 10 are made, the material 7 is given a chord-like cut 11 preferably parallel to and of the same length as the chord 10, and a second and substantially radial cut 12 which is preferably substantially the perpendicular bisector of the chord 11. Thus are

formed the piece 13 which is to constitute the shelf of the device, having two longitudinal straight line substantially parallel edges and two convex arcuate edges 14 and 15, and two corner pieces or braces 16 and 17, each having one side which is half the length of a side of the piece 13 and a right angularly related side represented by the cut 12, and each having for its third and remaining side, an arcuate edge 18. The material defined by the chord-like cut 10 and the notch cuts 9 is removed by the respective cutting or stamping operations.

The outer, generally annular piece 19 has substantial areas at its corners 20, which furnish sufficient material from which details employed in connection with the construction of the rack may be stamped. These details will be taken up in order as the building up of the rack is described.

The stamping operations with respect to the disc 5a having been completed as above described, the frame 5 thus remaining is subjected to an operation whereby its inner and outer margins 22 and 28 are bent substantially at right angles to the body of the frame 5 and in the same direction to lend a smooth outline when viewed from the front as seen in Figure 2. The notches 9 make it possible for the chord-like flange or lip portion 21 to be bent free of the remainder of the interior flange 22 and to project preferably somewhat farther rearwardly of the front face 23 of the frame 5. The shelf 13 has one longitudinal margin 24 thereof bent at right angles to the body as shown in Figures 3 and 7, and at that point is arranged to fit snugly below the flange portion 21 of the frame 5.

The means for supporting and firmly holding the shelf 13 in place will now be described.

Substantially rectangular clips 25 are stamped from one of the corners of the material 19 and preferably somewhat less in length than the short sides 12 of the corner pieces 16 and 17. The clips 25 are bent longitudinally so that one longitudinal margin 26 of each is laterally offset from the other margin thereof a distance substantially equal to the thickness of the material. The clips 25 are then arranged in spaced and parallel relation below the flange or lip 21 of the frame 5 and spot welded as at 25a or otherwise suitably permanently secured to the same so that the laterally outwardly extending margins 26 are spaced from the frame 5 to provide receiving sockets 27.

Each brace 16, 17 is formed at its short side and parallel thereto adjacent its long side with a slit or cut, leaving a tongue 29 which is bent into right angular relationship to the plane of said brace. The short margin 30 of which the tongue 29 is a part is then bent along substantially the line of the slit or cut, to a substantially right angular relationship to said brace, the tongue 29 thereupon substantially contacting the body of the brace and forming with said body and the bent margin 30 a solid angle of substantially 90°. The arrangement is such that the tongue 29 when so located is spaced from the longitudinal edge 31 of the brace a distance substantially equal to the distance from the upper extremity of the adjacent clip 25 and the flange or lip 21, less twice the thickness of the material. The flange or bent margin or lip 30 of the brace, when slipped or hooked into the socket 27, has its tongue 29 firmly in engagement with the upper end of the adjacent clip 25, and the longitudinal edge 31 firmly engages the lower surface of 75

the shelf 13, the fit being snug so that the shelf member is held firmly in the relationship shown in Figure 3. To insure the firm positioning of the braces 16 and 17 and consequently the firm 5 security and support of the shelf member 13, each brace is so formed that the length of the short side thereof is equal substantially to the distance between the lower surface of the shelf member 13 and the inner surface of the flange 28, measured substantially along the clip 25 at each 10 side of the vertical center of the frame 5. This is clearly shown in Figure 5, wherein each brace is shown at 32 to substantially engage the flange 28 at the outer peripheral margin of the frame 5.

15 In assembling the shelf 13 and braces with the frame 5, it will be understood from the foregoing that the shelf is first positioned with its bent margin 24 arranged against the rear face of the frame 5 below the flange 21 thereof, so that the 20 body of the shelf 13 extends substantially horizontally rearwardly or in a plane at substantially right angles to the plane of the frame 5. This may be done perhaps more conveniently by placing the frame 5 so that it rests on a substantially 25 horizontal support with its front side downward, and then positioning the shelf 13 as just stated. Each of the braces is then placed so that its plane is at substantially right angles to the plane of the frame 5, substantially as indicated by the 30 dotted lines 16a and 17a in Figure 5. When so arranged, the margin 30 is partially positioned in the adjacent pocket 27 of the clip 25, and the adjacent curved edge 32a is in substantial engagement with the flange 28 of the frame 5. The 35 braces are then swung bodily until the same are at substantially right angles to the shelf 13, the flanges 30 being thereupon further lodged in the pockets 27, the tongues 29 snugly engaging the upper extremities of the clips 25 adjacent the 40 shelf 13, and the longitudinal edges 31 of the braces snugly engaging the adjacent face of the shelf 13. It will be observed that sufficient clearance is provided between said extremity of each 45 clip 25 and the free edge of the depending flange 24 of the shelf 13 to enable the tongues 29 to swing thereinto.

When the parts are thus positioned, the portion 32a of the curved or arcuate edge of each corner piece or brace is in snug or biting engagement with the frame flange 28, and the pressure of the corner pieces against the shelf 13 serves to hold the same firmly in position against accidental removal. The margins 30 of the corner 50 pieces 16 and 17 are formed to fit snugly in the pockets 27, so that the structure as just described is substantially rigid.

To the end that the rigidity of the structure may be made more complete to prevent wobbling and to prevent accidental disassembly, a strut is 55 employed to connect the corner pieces 16 and 17 together. For this purpose, preferably rectangular strips 33 are stamped from a corner 20 of the material 19 as shown in Figure 1. Each of the strips 33 is bulged at its center at 34 so that its 60 plane at the center is offset from the plane of the remainder of the strip by substantially the thickness of the material. Each of these strips is positioned flatwise against the inner face of its respective corner piece 16, 17, preferably somewhat 65 spaced from and generally parallel to the short margin 30. The particular location of the strip with respect to each corner piece is immaterial so long as it serves its intended purpose. The member which is to constitute the strut comprises a 70 strip or strap 35 which is also stamped from a 75

corner of the material 19 as shown in Figure 1, and has its short ends bent in the same direction as shown at 36. With the corner pieces 16 and 17 arranged as pointed out hereabove and as shown in the drawings, the pockets 37 formed between the respective corner pieces 16 and 17 and the bulged portions 34 of the strips 33 are spaced apart substantially the distance between the bent portions 36 of the strip 35. While the parts 16 and 17 are snugly assembled as heretofore described, there is nevertheless a slight flexibility which enables them to be pivoted a slight amount outwardly away from each other about their anchored margins 30 to facilitate the positioning of the strap 35 therebetween and enable the bent portions 36 of the strap to be forced snugly into hooked relation to the pockets 37. The fit is fairly tight and snug to insure against accidental separation, and yet is of such a character as to permit forcible separation as when it is desired 20 to dismantle the rack. The strap thereby firmly holds the corner pieces 16 and 17 in the desired 25 spaced relationship with the margins 30 thereof securely fitted in the pockets 27 afforded by the frame 5 and clips 25. It will thus be observed 30 that the shelf 13 is securely positioned as if it were welded or otherwise permanently secured, yet the task of dismantling the parts would require but a moment.

It is desirable, though not absolutely necessary, 35 that the rack be supported on a base such as a counter or showcase in a store. To this end, a pair of legs 38 are stamped from a corner 20 of the annular piece of material 19, and for the purpose of rigidity, each leg 38 is bent longitudinally to a cross sectionally angular shape. At points substantially removed rearwardly from the margins 30 of the corner pieces 16 and 17, respectively, the angular legs are pivotally secured at 39 as by rivets to said corner pieces, the pivotal 40 connection being however such as to frictionally hold the legs 38 so that the same may be turned from the operative position shown in Figure 3, for example, to the inoperative position shown in dotted lines in that figure at 38a, and held by 45 friction in such inoperative position.

To insure stability of the rack as a whole, the arrangement of the leg construction is such that the shelf 13 is inclined slightly downward from the horizontal. This is made possible by constructing the legs 38 so that their feet 40 are arranged rearwardly of the vertical plane of the pivots 39 as seen in Figure 3.

The feet 40 are held against further rearward movement by means of abutments 41. The abutments 41 are obtained by being stamped from a corner 20 of the substantially annular piece of material 19 and are spot welded at 41a or otherwise suitably secured to the corner pieces 16 and 17. Each part 41 has a rearwardly extending 60 portion 42 which is laterally offset to provide a pocket for the reception of the upper end 43 of the respective leg 38, the shoulder at the forward end of the offset portion 42 abutting said upper end 43.

In a display stand or rack of this character, it is desirable to provide means for supporting a mirror, preferably at the rear end of the shelf or platform. To this end, a strip 44 of preferably the same material, which may be cut or stamped from a longitudinal margin of the shelf part 13, and of a length substantially commensurate with the longitudinal margin referred to, is given a transversely angular shape. The rear margin of the platform 13 is similarly formed so that it is 70 75

provided with an upstanding flange 45, and the angular piece 44 spot welded or otherwise suitably secured to the shelf 13 so that one of its arms extends upwardly in substantial parallelism and fairly close to the flange 45 as shown at 46 in Figure 7. The portions 45 and 46 extend upwardly sufficiently to provide a fairly deep trough for the reception of the lower end of a mirror or a frame enclosing a mirror, suitable instrumentalities being provided, of course, for fastening the mirror in position. Such instrumentalities may take any form, and for the purpose of facilitating such fastening, holes may be provided in the bottom of the trough formed by the portions 15 45 and 46 for the reception of screws, nails or the like for embedding in the mirror frame.

The angular piece 44 may, as stated, be formed from the originally formed shelf piece 13, or, if desired, may be stamped from a different piece 20 of stock. The upstanding portion 46 is preferably cut on a bias at its ends to assume substantially the same shape as the upstanding portion 45 of the shelf 13, so that, when viewed from the front, no part of the portion 46 projects or is 25 visible beyond the portion 44.

The construction and assembly of the parts of the stand or rack have been described hereinabove. It will be observed that the rack is supported by the lowermost part of the frame 5 and 30 by the legs 38, so that a rigid three point support for the rack is provided. It will be observed that the center of gravity of the stand is in a plane well to the rear of the lower supporting extremity of the frame 5, thus insuring stability against 35 tipping, and between the vertical planes passing through the feet 40 and extending at substantially right angles to the plane of the frame 5, whereby lateral tilting or tipping of the stand is inhibited for practical purposes.

40 It will be seen from the foregoing that just as the parts may be assembled readily and easily, so may they be disassembled. Thus the device as a whole may be shipped in such a manner as to occupy substantially the same space as would 45 be required in shipping the frame 5 alone.

It may be found advantageous under some circumstances to support the rack or stand by suspension instead of on legs as heretofore described. Provision for such a contingency is made in connection with the above described construction. 50 To this end, a clip 47, stamped from a corner of the substantially annular piece 19, and a hanger 48 are employed. The arm 48 is preferably formed from rod material and is given a substantially L-shape, including an arm 49 which, at 55 its outer surface, is serrated at 50 or otherwise roughened, the other arm 51 remaining preferably smooth. The clip 47 has its end portions substantially in the same plane, but its intermediate portion is made part cylindrical as shown at 52 to fit fairly snugly around a part of the correspondingly shaped arm 51 of the hanger 48, as shown in Figure 5. The height of the hanger 48, measured along the arm 51 thereof, 60 it will be observed, is not in excess of the space afforded between the flanges 22 and 28 of the frame 5, and the clip 47 is spot welded as at 47a to the upper part of the frame 5 between said flanges, with the bottom of the hanger 48 adjacent the part 51 normally resting upon the flange 22. The length of the part 49 of the hanger 65 may be of any desired dimension, but is preferably such that, when swung into a plane substantially parallel to the plane of the frame 5, it fits

against the body of the frame and between the flanges 22 and 28 as clearly seen in Figure 5.

When the rack is desired to be supported upon its legs, the part 49 of the hanger 48 is preferably swung into the inoperative position shown in Figure 5 and as shown in full lines in Figure 3. When it is desired to support the rack by suspension, the legs 38 are swung to the inoperative positions 38a, the part 49 of the hanger 48 is swung into the position shown in dotted lines in Figure 3, and the suspending means such as wire or the like looped under the part 49 and into engagement with one or more of the serrations 50, whereby slipping is prevented and the rack is properly supported. It will be observed that the length of the part 49 of the hanger 48 is sufficient to permit the same to be engaged by the supporting wire or the like at any of a number of positions in order that the instrumentalities displayed by the stand may be supported vertically or at any 15 desired angle to the vertical.

As will be seen from Figure 2, the display stand or rack constructed in accordance with the principles of the present invention is extremely attractive and when employed as intended materially 25 improves the appearance of the section of the room in which it is placed. It may be polished, chrome plated or enameled and provided with any desired design to improve its artistic effect, and may be used to advantage with or without a 30 mirror, although the latter is preferably employed not only to better show off the articles placed on the platform 13 in front of the same, but also to perform its own function when used by patrons of the establishment in which the stand appears. 35

As pointed out hereinabove, with the exception of the hanger 48, which is an auxiliary instrumentality for use only when it is desired to suspend the display rack, substantially the entire rack construction is formed from material which would 40 otherwise and in fact has heretofore been sold as scrap remaining from the substantially square blank from which tire cover side plates are stamped. The construction of the stand involves an ingenious method of manufacture insofar as 45 its basic elements are concerned, namely the frame, shelf and supporting corners or brackets, in that these elements are shaped and arranged so that they are made from a disc, said disc being the material which remains at the center of the 50 blank after the annular side plate of the tire cover is blanked or stamped out.

This is moreover accomplished with substantially no waste of material from the original disc.

It will be understood that the relative dimensions of the parts illustrated on the drawings are merely intended to be exemplary, since it will be understood that the width of the platform 13 and the size of the corner pieces 16 and 17 may be varied without requiring any change whatever in 55 the outer periphery of the frame 5. It is to be noted, of course, that the size of the corner pieces 16 and 17 should be such that they will afford adequate support for the shelf 13, both as regards the extent to which said pieces project rearwardly 60 under the shelf 13 and the extent to which they are spaced apart when they are assembled to snugly engage the lower portions of the outer flange 28 of the frame 5 as for example shown at 32, and the lower face of the shelf 13.

70 While the invention has been described as contemplating the use of sheet metal, where the tire cover side plate is made of the same material, it is understood to be well within the province of the present invention to construct the stand or 75

rack of any other suitable stiff sheet material of which tire cover side plates may be formed, such as hard rubber, cardboard, pressed wood, phenolic condensation products or the like. Of course, the 5 rack may be constructed from any desired stock, not necessarily the material which heretofore has been sold as scrap resulting from the manufacture of tire cover side plates, but it is to be understood that one of the features of the present invention 10 consists in the adaptation of such scrap material to the manufacture of the rack.

While the construction heretofore described is such that a certain degree of friction exists between the legs 38 and the respective corner pieces 15 16 and 17 to resist accidental pivoting of the legs, nevertheless, if desired, suitable positively acting holding means such as a latch, spring or gravity operated, may be employed to rigidly hold the legs in the position shown in Figure 3.

20 It is preferred that the frame 5 be imperforate as shown. However, if desired, the clips 25 providing the pockets or sockets 27 could be made integral with the frame by merely striking back corresponding portions so that they are offset just 25 as are the parts 26. Similarly, the retaining sockets or parts 33 and 41 could be provided. Also, instead of striking out the legs 38 and strut 35, and other parts, if desired, from the annular piece 19, such parts could be struck out from appropriate portions of the frame 5, or preferably 30 from the platform 13 and/or brackets 16 and 17. These cuts could be arranged so as not to detract from, but possibly improve, the appearance of the respective parts.

35 In Figure 3, a plaque or mirror is shown fragmentarily at 47a, disposed in the trough 47.

It will be observed from the foregoing that the frame at the chord 10 and the outer peripheral portion below said chord affords abutments engageable to enable the shelf to be rigidly mounted 40 on the frame.

I am aware that many changes may be made and numerous details of construction may be varied through a wide range without departing 45 from the principles of this invention, and I therefore do not purpose limiting the patent granted hereon otherwise than necessitated by the prior art.

I claim as my invention:

50 1. A knockdown display rack comprising a supporting member having a body and a ledge, a shelf having a margin under the ledge and a lip engaging the body adjacent the ledge, a pair of brackets, each having margins meeting at an angle, one margin of each bracket being bent 55 and engaging said body and said lip, the edge at the other margin engaging said shelf to support the same, said bent margin having an abutment at an angle thereto, means affording sockets 60 for releasably receiving the bent margins, said means being engaged with said abutments to thereby hold said edges at the other margins of the brackets in engagement with the shelf, and

a retainer releasably interlocked with said brackets to prevent escape of the bent margins from the sockets.

2. A knockdown display rack comprising a supporting member having a body and a ledge, a 5 shelf having a margin under the ledge and a lip engaging the body adjacent the ledge, a pair of brackets, each having margins meeting at an angle, one margin of each bracket being bent and engaging said body and said lip, the edge at 10 the other margin engaging said shelf to support the same, said bent margin having an abutment at an angle thereto, means affording sockets for releasably receiving the bent margins, said means being engaged with said abutments to thereby 15 hold said edges at the other margins of the brackets in engagement with the shelf, a retainer releasably interlocked with said brackets to prevent escape of the bent margins from the sockets, and legs connected to said brackets and 20 cooperating with said member to support the rack.

3. A display rack formed essentially from a disc of sheet material, comprising a substantially annular frame constituting the outer part of the 25 disc, and a platform and brackets therefor constituting together substantially the remainder of the disc without waste material, said platform extending from the inner periphery of the frame and at an angle thereto, and each of said brackets 30 having angularly related edges respectively engaging the frame and platform to hold the same at said angle to each other, said frame having spaced parts between which said platform and brackets are tightly fitted. 35

4. A display rack structure including a substantially planar frame having abutment means adjacent its inner periphery and other abutment means spaced therefrom, a substantially planar shelf member engaging the inner abutment means 40 and extending at an angle to the frame, and substantially planar bracing members wedged between the shelf member and the outer abutment means for bracing the shelf member at said angle to the frame, said members being of such 45 shape as to fit substantially without overlapping in the confines of the frame when the rack is dismantled, so as to occupy a minimum shipping space.

5. A display rack construction comprising a 50 sheet metal frame having outer and inner abutment means, said inner means being bent to provide angularly related surfaces, a sheet metal shelf plate having a margin bent to provide similar surfaces engaged with the aforesaid surfaces 55 to position the shelf at an angle to the frame, and substantially rigid bracing means wedged between said outer means and the plate to hold the respective surfaces in interengagement and constituting the sole means for holding the rack 60 in assembly.

HERBERT W. TINKER.
